[57] CLAIM

The ornamental design for a powered speaker, as shown and described.

DESCRIPTION

FIG. 1 is a top front and right side perspective view of the powered speaker showing our new design;

FIG. 2 is a front elevational view thereof;

FIG. 3 is a front elevational view of a second embodiment of the design of FIG. 1, the only difference being the omission of the controls from the front;

FIG. 4 is a right side elevational view of FIG. 1, the left side being a mirror image;

FIG. 5 is a right side elevational view of FIG. 3, the left side being a mirror image;

FIG. 6 is a top plan view of FIG. 1;

FIG. 7 is a top plan view of FIG. 3;

FIG. 8 is a bottom plan view of FIG. 1;

FIG. 9 is a bottom plan view of FIG. 3; and,

FIG. 10 is a rear elevational view of FIGS. 1 and 3.
